(57) CLAIM

The ornamental design for an outsole of a shoe, as shown and described.

DESCRIPTION

FIG. 1 is a perspective view of an outsole of a shoe showing my new design;

FIG. 2 is a plan view of the outsole of a shoe shown in FIG. 1;

FIG. 3 is a side view of the outsole of a shoe shown in FIG. 1;

FIG. 4 is another side view of the outsole of a shoe shown in FIG. 1;

FIG. 5 is a front view of the outsole of a shoe shown in FIG. 1; and,

FIG. 6 is a back view of the outsole of a shoe shown in FIG. 1.

The phantom lines showing portions of a shoe in FIGS. 1-6 are for illustrative purposes only and form no part of the claimed design.

The black irregular outline is understood to represent a boundary between claimed and unclaimed subject matter.
